UNITED STATES PATENT OFFICE.

HARRY LOCKWOOD VAUGHAN, OF CHICAGO, ILLINOIS.

BOTTLE-OPENER.

1,029,645.

Specification of Letters Patent. Patented June 18, 1912.

Application filed October 3, 1910. Serial No. 585,125.

To all whom it may concern:

Be it known that I, HARRY Lockwood VAUGHAN, citizen of the United States, residing at Chicago, in the county of Cook and 5 State of Illinois, have invented certain new and useful Improvements in Bottle-Openers, of which the following is a specification.

This invention relates to improvements in 10 bottle openers and especially to crown seal removers.

It has for its object to provide a device for removing crown and other similar seals from bottles without injuring the bottle.

15 Another object is to provide a simple, durable and inexpensive device of this nature, which may be attached to a base.

Another object is to provide a combination bottle opener and match scratcher.

20 With the above and other objects in view, I have invented the device illustrated in the accompanying drawings which is an improvement over Patent No. 943,759, issued to me on December 21, 1909. I found the 25 device covered by the above patent, defective, in that it had a tendency to bind the mouth of the bottle and cause it to chip or crack. This difficulty I have obviated in the present invention.

30 Referring to the accompanying drawings, Figure 1 is a perspective view of my improved bottle opener attached to a base, and Fig. 2 is an end elevation of the device showing it in operation.

35 Referring to the drawings 1 indicates a base to which my bottle cap remover is secured by means of two screws or nails 2 and 3. The device is made preferably of a piece of sheet metal having a certain resiliency 40 and consists of a supporting base 4 having a right angular projection 5 which may be roughened in order to form a match striking surface. The forward edge 6 of the right angular portion 5, is semi-cylindrical, 45 and the free edge 7 of this cylindrical portion is bent up at right angles to form a cap engaging member. The metal is doubled at 7 upon itself to form a two ply cap engaging hook. At a subcentral position however,

50 the plate gradually diverges from the angular portion 5 until its end 11 is in a plane parallel to the base 1. A cap engaging groove 10 is formed adjacent the end 11. This depending portion 11 acts as a brace 55 for the other parts of the device but is not

fixedly secured to the base contacting the same only at the bend of the groove when a bottle cap is being removed as indicated at 12, thus if too great a strain should be exerted on the device, the brace will give 60 and slide up and down rather than bind too tightly upon the bottle, thus acting as a cushion therefor.

When it is required to remove the cap 14 from the bottle 13 it is placed in position in 65 the device as illustrated in Fig. 2, and the bottle given a very slight movement toward the base 1, when the upturned flange 7 will pry the cap off. It will be noted that there is no pressure brought to bear against the 70 bottle, therefore there will be no tendency to chip the mouth of the bottle as in most other openers.

Having described my invention I claim and desire to secure by Letters Patent:— 75

1. A bottle cap remover consisting of a base having a resilient depending cap engaging member, the edge of said depending member being upturned, and a resilient brace for said depending member. 80

2. A bottle cap remover consisting of a base having a resilient depending cap engaging member, the edge of said depending member being upturned, a brace for said depending member, said brace having a groove 85 therein.

3. A bottle opener consisting of a fixed base having a right angular extension, said extension having a semi-cylindrical end adapted to engage the cap of a bottle and a 90 resilient brace therefor.

4. A bottle opener consisting of a fixed base, having a right angular extension, said extension having a semi-cylindrical member adapted to engage the cap of a bottle, said 95 semi-cylindrical member having an upturned portion, a brace for said semi-cylindrical member, said brace having sliding movement on its base.

5. A bottle opener consisting of a fixed 100 base having a right angular extension, said extension having a semi-cylindrical member adapted to engage the cap of a bottle, said semi-cylindrical member having a right angular upturned portion, an integral brace for 105 said cap engaging portion, said brace having a groove therein adapted to engage the edge of a bottle cap.

6. A bottle opener consisting of a base having a right angular extension, terminat- 110

ing in a semi-cylindrical portion, having its free edge turned up at an angle thereto, said semi-cylindrical portion being doubled to form a stiffening therefor.

5 7. A bottle opener consisting of a base having a right angular extension, terminating in a semi-cylindrical portion, having its free end turned up at a right angle thereto, said semi-cylindrical portion being doubled 10 to form a stiffening therefor, and means for bracing said semi-cylindrical portion.

8. A bottle opener consisting of a base having a right angular extension, terminating in a semi-cylindrical portion, having its 15 free end turned up at a right angle thereto, said semi-cylindrical portion being doubled to form a stiffening therefor, means for

bracing said semi-cylindrical portion, and a groove in said bracing means.

9. A bottle opener consisting of a base 20 having a right angular extension terminating in a semi-cylindrical portion having its free edge angularly inclined, said semi-cylindrical portion being double to form a stiffening therefor, said stiffening portion 25 extending rearwardly and being bent down on a line short of said base line to form a flexible cushion.

In testimony whereof I affix my signature in presence of two witnesses.

HARRY LOCKWOOD VAUGHAN.
